United States Patent Office

Des. 196,278
Patented Sept. 10, 1963

196,278

PHOTOCOPY MACHINE

Philip B. Novick, Bayside, N.Y., assignor to Analogue
Controls Inc., Hicksville, N.Y., a corporation of New
York

Filed Dec. 18, 1962, Ser. No. 72,894

Term of patent 14 years

(Cl. D61—1)

T 19.2.

FIG. 3.

FIG. 4.

FIG. 5.

FIG. 1 is a front perspective view of a photocopy machine showing my new design;

FIG. 2 is a top plan view thereof;

FIG. 3 is a front elevational view thereof;

FIG. 4 is a right-side elevational view thereof; and

FIG. 5 is a rear elevational view thereof.

I claim:

The ornamental design for a photocopy machine, as shown.
